UNITED STATES PATENT OFFICE

OTHO V. KEAN, OF PROVIDENCE, RHODE ISLAND

PLASTER-BOARD STRUCTURE

Application filed April 25, 1927. Serial No. 186,278.

This invention relates to an improved plaster board of fire-proof construction and method of making the same which is adapted for application to the walls and ceilings of rooms, for which purpose the same may be formed in standard sizes as desired for a particular use.

One object of the invention is to provide a plaster board or wall board of the character described which is highly resistant to fire as well as one in which the tendency to crack is reduced to a minimum.

A further object of the invention is to provide an effective metal binder or internal support for the plaster board which is adapted to bind the material of which the plaster board is formed firmly together and tend to support the same against separation at all times, as well as to provide a support by which the plaster board may be firmly secured to the frame members to which it is applied in use.

Another object of the invention is to provide a plaster board of the character described which is of substantially fire-proof construction and is provided with a metal gridwork or frame embedded within the material of which the plaster board is formed in such a manner as to serve as a support for the material and to prevent warping or buckling of the plaster board, and at the same time provide a means by which the plaster board may be secured to the frame members to which it is applied.

Other objects and advantages of the invention relate to certain novel details of construction and improved methods of operation as will be more fully set forth in the detailed description to follow.

Referring to the drawings:—

Fig. 1 is an elevational view of a portion of a sheet of plaster board made in accordance with the present invention and having layers broken away to show the various parts and the manner of assembling the same,

Fig. 2 is a detail plan view of a portion of a metal gridwork or frame such as may be employed in the construction of the plaster board,

Fig. 3 is a detail plan view of an edge por-

tion of another form of metal gridwork or frame such as may be employed in the construction of the plaster board, and

Fig. 4 is a perspective view of one of the main strands forming the metal gridwork wound with a thread of asbestos.

In the manufacture of plaster board or wall board for use upon the walls or ceilings of rooms it is desirable that such material be so formed that it will not warp or buckle while in use, and at the same time be so constructed that the initially plastic material forming a part thereof be supported through its extent, particularly when used in large sheets, to prevent breakage of the same. It is also particularly desirable in modern construction to provide material of this character which is of fire-proof construction throughout, and also provide means by which the material may be firmly secured to the frame members of a building whether such frame members be of wood or metal.

In order to satisfy the foregoing requirements and provide a plaster board which is high efficient for general purposes and, which can be readily prepared I propose to form a plaster board by embedding within the initially plastic material a metal gridwork or frame so constructed as to tend towards providing a firm support for the material and at the same time provide means for securing the plaster board to the frame of the building.

In Fig. 1 of the drawings the plaster board sheet 1 is composed of outer layers 2 and 3 of initially plastic material which is pressed against a metal gridwork 4 so formed as to permit the material to extend through a plurality of openings in the gridwork, and thus form a coherent mass about the gridwork so that upon solidification the sheet will form a unitary structure without any tendency for the opposite layers of material to separate from the metal gridwork.

The metal gridwork 4 as shown, is made up of a woven wire mesh 5, which may be formed of strands of any desired cross-sectional configuration, but which in the present instance are formed of wires 6 which are of segmental cross-section, since this form of

wire is found to be well adapted for the purpose as presenting a relatively large area to the initially plastic material in proportion to the weight of the wire.

5 In the form of the invention shown in Fig. 1 a perforated sheet metal border plate 7 is provided which surrounds the wire mesh 5 and to which the ends of the strands 6 are secured as at 8, the metal border plate 7 is provided with a plurality of openings 9 of a size and number sufficient to permit the initially plastic plaster material upon opposite sides to extend therethrough and thus prevent any cleavage from taking place on either 10 side of the plate 7. The plate 7 is sufficiently thin to permit the usual fastening devices being driven therethrough to secure the plaster board sheet to the wooden frame members of a building, whereby the metal plate 7 15 assists in securing the plaster board securely in place thereon.

20 In the form of the invention shown in Fig. 3 of the drawings the wire mesh 5 is similar in all respect to that previously described as 25 are the strands 6 of which it is composed. The border 11, however is formed of a somewhat finer woven wire mesh 12, and the ends of the strands 6 are secured thereto in any suitable manner, such as being bent through 30 the wire mesh 12, soldered thereto, or spot welded, or otherwise secured thereto. The wire mesh 12 is sufficiently coarse to permit the plaster, in its initial plastic state, to enter the interstices in the mesh and thus form 35 a coherent mass extending through the spaces in the mesh, and as in the previous construction suitable fastening devices may be forced through the wire mesh 12 and into the wooden frame members whereby the plaster board 40 may be securely held in place.

45 Fig. 4 illustrates a wire strand of segmental cross-section such as is preferably employed in forming the gridwork as shown in Figs. 2 and 3, the same being wound with an asbestos thread 14. While it is preferred to employ a wire of segmental cross-section as shown for forming the mesh portion of the gridwork, a wire of any other cross-sectional form may be used, and while as shown in Fig. 50 4, the wire may be wound with asbestos thread to cause the initially plastic material to more firmly adhere thereto, the asbestos thread may be braided upon the wire or otherwise secured thereto. While the wire forming the mesh 55 may be covered with asbestos thread, wound, braided, or otherwise applied thereto, the wire forming the mesh may also be employed without the asbestos thread covering.

60 It is to be understood that the wire mesh 5 is shown as in the form of a square weave, a triangular, hexagonal, or any other suitable weave may be employed, and that the metal gridwork may be formed in various other ways, such for example as, from unwoven 65 strands, without departing from the spirit

and scope of my invention. While I have shown and described my improved plaster board more particularly for attachment to the wooden frame members, I may so construct the same as to permit its application to metal frame members, by providing suitable spaced openings in the periphery thereof for the insertion of suitable attaching means, or even by allowing the edge of the border plate to project slightly beyond the edge of the 70 plaster for attachment to the metal frame members of the building, in which case the narrow space separating adjacent plaster board sheets may be filled by applying a thin layer of plastic material thereto. 75

80 In the various forms of wire mesh construction shown and described the wire forming the mesh is of segmental cross-section, similar to that shown in Fig. 4 of the drawings, and the separate strands forming the 85 mesh are so arranged that the maximum diameter of each substantially coincides with the plane of the wire mesh, as is indicated by the forms of the structure shown in Figs. 2, 3 and 4 of the drawings.

90 The initially plastic material employed for forming the plaster board may be of any suitable or desired composition and may be applied to the metal gridwork in any desired manner, but I prefer to form the same from 95 a mixture of gypsum and asbestos fibre thoroughly mixed together, to which a small quantity of sodium silicate may or may not be added to increase the adhesion of the material to the metal parts of the gridwork. A sufficient quantity of asbestos fibre is mixed with 100 gypsum to produce a fibrous effect in the plastic material and thus more firmly bind the material after it becomes set, but any other suitable fibrous material may be used in place 105 of the asbestos fibre, and any other form of the plaster material may be substituted for the gypsum if desired. I have mentioned the gypsum as the preferred material since I have found it to be well adapted for the purpose, and prefer to employ asbestos fibre as the 110 fibrous material to be used in connection therewith because of its fireproof qualities. The metal forming the strands 6 and border portion of the gridwork is preferably annealed or formed of metal sufficiently soft to permit it to be cut readily so that the sections of plaster board with metal gridwork 115 embedded therein, may be cut to size when desired, and the border portion may be made as shown in the drawings or of any other suitable form of fine mesh metallic material providing openings therein for the initially plastic material and so made as to permit 120 nails or other fastening devices being driven therethrough.

125 What I claim is:—

1. An improved article of manufacture comprising a wire mesh formed of wire which is of segmental cross-section, a metal 130

border for said wire mesh provided with a plurality of openings, the ends of the several strands of said wire mesh being secured to the border, and a composition material overlying the opposite sides of said wire mesh and border to form a plaster board section.

5 2. A plaster board section of the character described comprising a layer of initially plastic material mounted upon a metal gridwork, a portion of said gridwork being first wound 10 with asbestos fibre to more firmly secure the initially plastic material thereto.

15 3. An improved article of manufacture comprising a wire mesh formed of strands of segmental cross-section, the maximum diameter of which substantially coincides with the plane of the wire mesh, a metal border surrounding the wire mesh and to which the ends of the individual strands forming the wire 20 mesh are secured, and a composition material overlying the opposite sides of said wire mesh and metal border to form a plaster board section.

25 4. An improved article of manufacture comprising a wire mesh formed of relatively heavy wire of segmental cross-section and provided with a plurality of relatively large openings, a metal border for said wire mesh comprising a wire mesh formed of relatively 30 light wire and provided with a plurality of relatively small openings, the ends of the several strands of said first named wire mesh being secured to said second named wire mesh, and a composition material overlying the 35 opposite sides of the central wire mesh and the border wire mesh to form a plaster board section.

In testimony whereof I have affixed my signature.
